UNITED STATES PATENT OFFICE

109,059

DESIGN FOR A COOKING RANGE

Herman H. Heidbreder, Quincy, Ill., assignor to Southern Stove Works, Richmond, Va.

Application April 9, 1937, Serial No. 68,655

Term of patent 7 years

To all whom it may concern:

Be it known that I, Herman H. Heidbreder, a citizen of the United States and a resident of the city of Quincy, county of Adams, and State of Illinois, have invented a new, original, and ornamental Design for a Cooking Range, of which the following is the specification, and reference being had to the accompanying drawing, forming a part thereof.

The figure is a perspective view of a cooking range showing my new design.

That end of the range not showing in the perspective figure is substantially plain.

I claim:

The ornamental design for a cooking range as shown and described.

HERMAN H. HEIDBREDER.
